[57] CLAIM

The ornamental design for a cabinet, substantially as shown and described.

DESCRIPTION

FIG. 1 is a view in top plan of the cabinet showing my design;

FIG. 2 is a view in front elevation of the cabinet of FIG. 1; and,

FIG. 3 is a view in side elevation of the cabinet of FIG. 1, the opposite side being identical thereto.
The back of the cabinet is plain and conventionally flat.
